UNITED STATES PATENT OFFICE.

WILLIAM F. FISCHER, OF PHILADELPHIA, PENNSYLVANIA.

GRINDING-MACHINE.

1,182,362.

Specification of Letters Patent.

Patented May 9, 1916.

Application filed March 23, 1915. Serial No. 16,319.

To all whom it may concern:

Be it known that I, WILLIAM F. FISCHER, a citizen of the United States, residing at Philadelphia, in the county of Philadelphia and State of Pennsylvania, have invented 5 certain Improvements in Grinding-Machines, of which the following is a specification.

This invention is designed to provide a 10 machine of simple character that can be used for forming articles having various and eccentric shapes, and in its preferred construction it comprises a grinding wheel provided with truing means, in combination 15 with means provided with a follower co-operating with forms corresponding to the contours to be produced, whereby the wheel may be caused to cut irregular or regular configurations heretofore made at considerably greater trouble and expense than are 20 involved in manufacturing by my improvements.

The characteristic features of my 25 improvements are fully set forth in the following description and the accompanying drawings in illustration thereof.

In the drawings, Figure 1 is a plan view 30 of a machine embodying my invention; Fig. 2 is an elevation of the same; Fig. 3 is a sectional elevation taken on the line 3—3 of Fig. 2; Fig. 4 is an enlarged plan view 35 of the grinding wheel truing mechanism; Fig. 5 is a broken side elevation of the construction shown in Fig. 4; Fig. 6 is a top plan view of a preferred modified form of 40 the invention; Fig. 7 is a broken front elevation of the construction shown in Fig. 6; and Fig. 8 is a sectional view of a detail of the construction shown in Figs. 6 and 7.

The invention, in the form illustrated in 45 the drawings, is embodied in a machine comprising the pedestal 1 having thereon a slide or carriage 2 which is adapted to be reciprocated by means of a screw 3 turned by a hand wheel 4. The slide 2 has thereon a slide or carriage 5 adapted to be reciprocated transversely to the direction of movement of the slide 2; the slide 5 being provided with a rack 5' which is engaged by a 50 pinion 6 on a shaft 7 journaled in the slide 2 and turned by the handle 8, whereby the reciprocation is effected. The slide 5 is provided with a clamp 9, operated by a screw 10, by which is held a finger or follower 11 55 adjustable longitudinally and fixed in the desired position, the finger having a spheri-

cal point 11' of say one-fourth inch radius to coöperate with the former. The bearings 12 on the slide 5 have journaled therein an arbor 13 on which is fixed a grinding wheel 60 14 having a rounded periphery 14' conforming in cross section to a longitudinal section through the point 11' to produce the desired configuration, the arbor 13 being disposed transversely to the finger 11. 65

A bracket 15 is carried by the pedestal 1, being adjustable transversely along the way 1' and clamped in position by bolts 16. A slide 17 is movable on the bracket 15 by means of a screw 18 which is turned by a 70 handle 19, the slide being movable in the direction of the follower 11. A form 20, having the contour 21, is fixed on the slide 17 by bolts 22 whose heads move in the ways 17' transverse to the movement of the 75 slide, whereby the form is adapted to be adjusted transversely.

A bracket 23, carried by the pedestal 1, is provided with a vertical sleeve 23' in which is disposed a stem 24, the latter being movable longitudinally by a screw 25 journaled in the bottom of the sleeve 23' and turned by a handle 25'. A head 26 is supported and adjustable vertically by the stem 24, the head having a slide 27 adjustably mounted thereon and fixed by bolts 28 having heads movable in the ways 29. 80 85

The blank of an article 30, to be ground, is fixed on the slide 27 by means of bolts 31 having heads movable in the ways 29' transverse to the ways 29, whereby the article can be adjusted transversely and fixed in the desired position with reference to the wheel 14. The form 20 having been fixed in correct 90 95 position on the slide 17, the latter is adjusted by turning the handle 19. The slide 2 is adjusted by means of the screw 3 through the operation of the wheel 4 so that the follower 11 touches a datum point of the form. The blank for the article 30 is fixed on the slide 100 27 in the same relation to the wheel 14 as has been established between the follower 11 and form 20. The article 30 is ground to a contour of the form 20 by the wheel 14, which is driven in any usual manner and guided 105 by keeping the follower 11 in contact with the contour 21, the desired movements being effected by turning the wheel 4 and handle 8. The vertical adjustment of the head 26 effected by operating the handle 25' provides for grinding in various planes, at various angles and to various forms, permitting 110

the operator to make successive cuts at the different elevations and angles required for producing the desired contour by means of the wheel.

5 The cutting face of wheel 14 is maintained in correct cross sectional contour by mechanism comprising a cutting or grinding device 32 (suitably a diamond) mounted in the end of a screw 33, the latter being set 10 radially with reference to a center or centering socket 34 disposed in the plane of the wheel 14 and movable longitudinally through a bearing or slide 35. The part 35 has a circular movement in the way 36' of 15 the head or slide 36 so that the diamond 32 is movable in a circular path having a radius determined by the longitudinal adjustment of the screw 33, whereby the periphery of the wheel 14 can be cut to a circular cross-section of any desired radius, the part 35 being 20 turned by a handle 35'. A pin 37', of the radius to which it is desired to bring the periphery of the wheel, is set in the center 34 and the screw 33 is adjusted to set the diamond 32 in contact with the pin, which is 25 then removed. The head or slide 36, which has been previously drawn back on the slide 37 by a screw 38 operated by a wheel 38', is now advanced so that the diamond makes 30 contact with the periphery of the wheel, which is trued by revolving it and oscillating the part 35. A lateral or transverse adjustment of the head 36, laterally adjusting the center of oscillation of the diamond 32, 35 is effected by the adjustment of the slide 37, which is movable by a screw 39 on a support 40, the latter being fixed on the slide 5.

As illustrated in Figs. 6, 7, and 8, the pedestal 1 has connected with its way 1' a 40 bracket 15' on which is mounted a housing 41 provided with the vertical bearings 41' and 41''. The bearing 41' contains a vertical sleeve 42 having a circular head or table 42' and a rack 42''. A pinion 43 engages the 45 rack 42'' to move the sleeve 42 vertically, and a worm wheel 44, which is turned by a hand operated worm shaft 45, turns the pinion, which is fixed thereto, these parts being journaled in the housing. A circular head 50 or table 46 is revolute on the head 42' by a shaft 47, which is fixed thereto and journaled in the sleeve 42, the shaft being movable through a gear wheel 48 to which it is connected and by which it is revolved 55 through a key 47'. The bearing 41'' has journaled on its circular head, a circular head or table 46' which is fixed to the top of a vertical shaft 49, the latter being journaled on the bearing. A gear wheel 50 is fixed to 60 the lower end of the shaft 49 and is connected with the gear wheel 48 through the intermediate gear wheel 51, the several gear wheels being inclosed in the housing. The head 46' is adapted for holding a form 52, the head having the circular T-slot 46'' for holding

the bolts 53 by which the form is fixed in position for coöperation with the follower 11 (operated as heretofore described), and the head 46 is similarly provided with a circular slot 46'' and bolts 53 adapted for holding an 70 article 54 to be formed by the wheel 14, operating as previously described.

As here shown, the pin or follower 11 is fixed to a slide 55 which is movable longitudinally in the way 56, to move the pin 75 longitudinally, by hand operated shaft 57, the latter being connected to the slide by a pinion and rack 6 and 5'. In this construction, the parts 52 and 54, having been fixed on the respective heads 46' and 46, the heads 80 are adjusted to the proper positions and clamped to the respective heads 41'' and 42' by means of bolts 58 drawn up by journaled levers 59 in which they are threaded. The machine is now operated so that the pin 11 85 follows the concave line 52' of the form 52 and the wheel 14 forms an analogous concave surface 54' in the form 54, the sleeve 42 being adjusted vertically to bring the material in different horizontal planes of 90 the part 54 into proper relation with the wheel. The concavity 54' having been formed and it being desired to form a convex surface 54'' on the article 54 analogous to the convex surface 52'' of the form 52, 95 the levers 59 are operated to loosen the bolts 58, the head 46' is turned by hand to bring the surface 52'' into proper relation with the pin 11, and the article 54 is thereby brought into analogous relation to the wheel 100 14 through the revolution by the head 46' of the parts 49, 50, 51, 48, 47 and 46. The parts being properly adjusted, they are fixed in position by operating the levers 59, and the machine is operated as before. 105

Having described my invention, I claim:

1. The combination of means for holding a form and an article to be formed, with a slide, a follower on said slide for tracing the outline of said form, a grinding wheel journaled on said slide for cutting said article, a second slide on which said first slide is movable to and from said means, and means whereby said second slide is movable transversely to the movement of said slide first 115 named.

2. The combination with a follower and a grinding device, of a revolute device for holding a form in correlation to said follower and a revolute device for holding an article to be 120 formed in correlation to said grinding device.

3. The combination with a follower and a grinding device, of a revolute device for holding a form in correlation to said follower, a revolute device for holding an 125 article to be formed in correlation to said grinding device, and means connecting said revolute devices whereby the revolution of one effects a similar revolution of the other.

4. The combination with a follower and a

grinding device, of a journaled shaft having a head thereon for holding a form in correlation to said follower, a journaled shaft having a head thereon for holding an article 5 in correlation to said grinding device, and means connecting said shafts whereby they are revoluble together.

5. The combination with a follower and a grinding wheel, of a journaled shaft having 10 a head thereon for holding a form in correlation to said follower, a longitudinally movable bearing, a shaft journaled in and movable longitudinally by said bearing, said last named shaft having a head thereon for 15 holding an article in correlation to said grinding wheel, and means connecting said shafts whereby they are similarly revolved.

6. The combination with a follower and a grinding wheel, of a journaled shaft having a head thereon for holding a form in correlation to said follower, a longitudinally movable and revoluble shaft having a head thereon for holding an article in correlation to said grinding wheel, and means connecting said shafts whereby they are similarly 20 25 revolved.

In testimony whereof I have hereunto set my name this 18th day of March, 1915, in the presence of the subscribing witnesses.

WILLIAM F. FISCHER.
